COMBINED CANISTERS AND CABINET THEREFOR

Arnold N. Schechter, Chicago, Ill.

Application June 27, 1958, Serial No. 51,575

Term of patent 14 years

(Cl. D44—6)

Fig. 1 is a front elevational view of combined canisters and cabinet therefor embodying my new design;

Fig. 2 is an end view of Figure 1;

Fig. 3 is a top view of Figure 1 shown to a reduced scale; and

Fig. 4 is a fragmentary and enlarged perspective view of the upper left hand corner of Figure 1.

The essential features of my design are shown in full lines.

I claim:

The ornamental design for combined canisters and cabinet therefor, substantially as shown and described.
